METHOD OF TREATING FUR

Jenny Jacobs, New York, N. Y.

No Drawing. Application July 15, 1937,
Serial No. 153,759

4 Claims. (Cl. 149—28)

The general object of the present invention is to provide an improved method of treating furs. More specifically, the object of the invention is to provide a method of subjecting fur pieces, and particularly wearing apparel articles, such as coats, muffs and neck pieces, to a simple treatment, which may be carried out by housewives and ordinary users of the above mentioned fur articles, and by which the article is subjected in the course of a single treatment to all or several of the following actions, namely: a fur cleaning action, a skin or hide oiling action, a glazing action, and moth repellent action, anti-septic, germicidal or other pest control properties to the fur piece.

The present invention is characterized by the working of a comminuted or granular treatment agent into and through the hairs of the fur piece treated, by a combing action. The latter may be carried out by means of a comb of the type ordinarily used by women in combing their hair. The treatment agent employed in accordance with the present invention, comprises a comminuted or granular base fibrous material, such as shredded leather, or ground asbestos fibers, having absorbent properties, and adapted to engage frictionally with the hairs of the fur piece treated and with the teeth of the comb by which the material is worked into and through the fur, and which is relatively soft, and does not have sharp edges tending to sever or break the hairs of the fur piece treated. The base material advantageously incorporates or is mixed with substances treated with, or comprising a hide or skin softening and preservative agent such as pine oil, a disinfectant or germicide such as phenol, and a glazing agent such as casein.

In the preferred mode of practicing the present invention, the treating agent is sprinkled over the fur piece to be treated, and is then worked into and through the hairs of the fur piece by a simple combing action. The effect of thus working a treating agent such, for example, as shredded leather impregnated with pine oil, phenol, and casein through the fur, is to oil the skin or hide base of the fur piece, to clean the fur in consequence of adherence of dirt in the fur to the fibrous treatment agent, to so distribute the phenol through the fur that only a relatively very small amount of phenol is required to insure an adequate moth repellent action, and to give the hairs of the fur a lustrous casein coating, which, in conjunction with the combing action,

causes the hairs to stand up, and thus produces a desirable glazing effect.

The combing action may be effected by the use of an ordinary comb of any form used by women in combing their hair, but preferably is not a metal comb, but a comb made of a strong moldable material such as a soy bean composition. The base treatment material may consist of one, or a mixture of two or more suitable substances. I have found it advantageous, to mix some granular cork with shredded leather in forming the treatment agent, as that mixture is free from a matting tendency, sometimes experienced when the base material consists only of shredded leather.

I am aware of prior proposals to use a granular material, such as particles of corn-oil-cake meal, sawdust, and ground corn cobs, usually saturated with gasoline or an analogous cleaning fluid, as a cleaning agent to be worked into, and beaten out of furs in a rotating tumbling barrel, or furs subjected to some other form of a beating or pounding action, but the tumbling barrel and beating fur treatments are not equivalent to the combing action employed by me, and the last mentioned materials do not have properties well adapted for use with my combing action.

Having now described my invention, what I claim as new and desire to secure by Letters Patent, is:

1. A method of fur treatment which consists in working a comminuted, relatively soft, solid fibrous material through the fur by manually combing said material into and through the fur, said material being impregnated with a hide softening, a pest control and glaze coating agents.

2. A method of fur treatment which consists in working a comminuted, relatively soft, material through the fur by manually combing said material into and through the fur, said material comprising shredded leather impregnated with a substance adapted to be transferred to the fur through which the material is worked.

3. A method of fur treatment which consists in working a comminuted, relatively soft material impregnated with a pest control agent through the fur by manually combing said material into and through the fur.

4. A method of fur treatment which consists in working a comminuted, relatively soft material impregnated with a glazing agent through the fur by manually combing said material into and through the fur.

JENNY JACOBS.
